UNITED STATES PATENT OFFICE.

JAMES A. JOHNSON, OF DANVILLE, VIRGINIA, ASSIGNOR TO DANVILLE CONDITIONING MACHINE COMPANY, INC., OF DANVILLE, VIRGINIA, A CORPORATION OF VIRGINIA.

YARN-MOISTENING MECHANISM.

Application filed June 18, 1923. Serial No. 646,094.

To all whom it may concern:

Be it known that I, JAMES A. JOHNSON, a citizen of the United States, residing at Danville, in the county of Pittsylvania and 5 State of Virginia, have invented certain new and useful Improvements in Yarn-Moistening Mechanisms, of which the following is a specification, reference being had to the accompanying drawings.

10 This invention relates to the conditioning or treating of yarn prior to its being wound in a winding machine, and particularly to means for supplying moisture to the yarn or conditioning it, as it is called.

15 In the ordinary conditioning of yarn, the yarn is wound upon cones and these are placed within the conditioning room where they are submitted to the action of moisture, the room being filled with a very fine spray 20 or vapor from a suitable spraying pipe. This moisture sets the twist and prevents kinking, but is objectionable in that the outside layers of the yarn on a cone must be moistened beyond the proper percentage 25 in order that the inside layers of yarn shall have the proper percentage of moisture.

The general object of the present invention is to condition the yarn by the provision 30 of means whereby the yarn is moistened as it is being wound upon the cone, and provide means whereby a uniform amount of moisture shall be supplied to all the yarn so that the inner layers of the yarn on the cone will have just as much moisture and no 35 more than the outer layers, thus preventing the mildewing of the outer layers.

A further object of the present invention is to provide a moistening device of this character which does not use rollers or like 40 rotating moistening devices and thus avoids any chance of the yarn, in case it breaks, getting wound up on the rollers.

A still further object is to provide a mechanism of this character which is very simple 45 and effective in its operation, and which is so constructed that it may be readily cleaned.

Another object is to provide a mechanism 50 of this character in which the yarn is moistened by means of two or more moistening members which are alternately immersed in a tank containing water or water and oil or any other liquid and which is disposed between the bobbins of a winding machine and the cones on which the yarn is wound,

and provide mechanism whereby these 55 moistening members are intermittently immersed and then raised into contact with the yarn, the mechanism being such that one of the moistening members is always in contact with the yarn and supplying 60 moisture thereto.

Other objects have to do with the details of construction and arrangement of parts as will appear more fully hereinafter.

My invention is illustrated in the accompanying drawings, wherein:—

Figure 1 is a fragmentary elevation of an ordinary winding machine showing my improvement applied thereto, parts of the framework of the machine being in section; 70

Figure 2 is a perspective view of a portion of a winding machine with my mechanism applied thereto;

Figure 3 is a transverse section on an enlarged scale taken through the moistening 75 members and showing in connection therewith one of the bobbins and one of the winding rollers;

Figure 4 is a longitudinal section through one end of the trough, showing the actuating levers for the moistening members; 80

Figure 5 is an elevation of the end of the trough and the operating levers illustrating the means whereby the operating levers are oscillated; 85

Figure 6 is a diagrammatic view of the operating crank disk in a different position from that shown in Figure 5;

Figure 7 is an elevation of the operating 90 crank disk and its parts;

Figure 8 is a diagrammatic view like Figure 6, but showing the position taken by the links and the bell cranks when the operating pulley has moved through the next succeeding quarter of a revolution; 95

Figure 9 is an elevation partly broken away of two sections of one of the moistening members;

Figure 10 is a sectional view through the trough showing the manner in which a drip apron or splash pan may be detachably mounted thereon; 100

Figure 11 is a fragmentary perspective view of one of the moistening members;

Figure 12 is a fragmentary perspective 105 view of a modified form of moistening member;

Figure 13 is a detail perspective view of

a moistening member like that shown in Figure 12 but slightly different therefrom;

Figure 14 is a diagrammatic top plan view showing the manner in which the thread or 5 yarn traverses the moistening member and the beveled portions thereof.

Referring to these drawings, it will be seen that I have illustrated a portion of an ordinary winding machine, in which 10 designates generally the frame of the machine. This carries the usual cones 11 driven by means of rollers 12 contacting with the faces of the cones upon which the yarn is wound. Disposed in front of each cone is a guide 13 10 upon which a traveler 14 is mounted for oscillation. This traveler causes the yarn to traverse the cone 11 from end to end so as to cause the uniform winding of the yarn upon the cone 11. The yarn *a* comes from the bobbin 15 which is supported in any suitable manner upon the machine. So far, I have described so much of an ordinary winding machine such as is commonly used in cotton mills. It will be understood, however, that my mechanism might be applied to any form of winding machine.

My moistening mechanism comprises a trough 16 adapted to contain water, water and oil, or any other desired liquid, this 30 trough being shown as mounted upon brackets 17, which in turn are bolted to a rail 18 forming part of the winding machine and ordinarily found thereon. This trough 16 may be made of any suitable material. One 35 wall of the trough is shown as being higher than the other wall and the front wall of the trough is shown as rounded, as at 19. This trough may be made of metal or wood. The trough has a length equal to the total 40 length of the winding machine and is supplied with water from any suitable source as, for instance, from the tank 19^a, the source of supply being such that the water within the trough is always kept at a uniform 45 level.

Disposed within this trough 16 are a pair of longitudinally extending moistening members 20 and 21. These members may be made of brass, wood, glass, hard fiber, porcelain or any other suitable material. While 50 I do not wish to be limited to the particular form of the members illustrated, I have shown these members as being U-shaped in cross section so as to provide two downwardly extending walls 22. These members are both alike and the description of one 55 will, therefore, apply to the other. The upper horizontal wall of each member is preferably rounded, with relatively shallow, 60 longitudinally extending ribs or corrugations 23. The upper surface of each moistening member, however, might be knurled, roughened or otherwise formed to hold water, it being the sole purpose of these ribs or corrugations to prevent the water from

running off of the moistening member too quickly. Each moistening member is preferably provided with a vent opening 24 at the middle of its horizontal wall. The moistening members have a depth less than the 70 depth of the water in the tank so that each moistening member may be fully submerged. Preferably each moistening member is formed of a plurality of sections, as shown in Figure 9, that is, in an ordinary moistening device for the ordinary winding machine each moistening member will be 40' long and formed of, say ten sections each 4' long. The sections are designated *b* and *c* in Figure 9. The sections are in alignment with each other and connected for longitudinal movement by any suitable means.

I have illustrated for this purpose a latch 25 which at one end extends down through the top wall of the section *b* and then extends longitudinally in a groove in the section *b* and has a downwardly extending end 26 which extends through the top wall of the section *c*. This latch 25 then engages the sections *b* and *c* for longitudinal movement but the latch will permit the sections to be readily lifted and removed from the tank one by one. As before remarked, I do not wish to be limited to the specific form of means for holding the sections together for longitudinal movement, as other means might be substituted for the one shown without departing from the spirit of my invention.

The lower edges of the side walls of each moistening member are formed with the inclined cam faces 27. There is a cam face 27 preferably at the opposite ends of each section *b*, *c*, etc., but it will be understood that there might be intermediate cam faces if desired. These cam faces operate against transversely extending ribs 28 formed upon the bottom of the trough, and thus it will be seen that when the moistening member is moved to the left in Figure 4 or to the left in Figure 9, that the cam faces 27 engaging the ribs 28 will cause the moistening member composed of the sections *b* and *c* and the connected sections to rise to an extent dependent upon the height of the rib 28, and that when the moistening member is moved in the reverse direction it will fall. This is shown in dotted lines in Figure 4. When the moistening member is submerged, the water in the tank will flow over the face of the moistening member and when it is raised some of this water will be carried up with the moistening member and will be applied to the yarn passing over the upper face thereof.

As before remarked, there are a pair of 125 these moistening members and mechanism must be provided whereby one of these moistening members is raised and the other depressed and whereby one of the moistening members is always held in contact with 130

the yarn until the other moistening member is raised into contact with the yarn, the first named moistening member being then depressed. I do not wish to be limited to the mechanism which I have illustrated for this purpose, as it is obvious that other means might be used, but I have shown each moistening member as being operatively connected to the depending arm 29 of a corresponding bell crank 30 mounted upon a transverse shaft 31 supported in brackets upon the trough at one end thereof. Each of these bell cranks has a horizontal arm 32. The depending arm of each bell crank is longitudinally slotted, and a pin 33 engages the walls of the corresponding moistening member and passes through this slot.

By this means it will be seen oscillation communicated to the bell crank levers will cause a reciprocation of the moistening members. The outer ends of the horizontal arms 32 of the bell cranks are connected to respective links 34 and 35. Mounted upon a bracket 36 or in any other suitable manner is a driving pulley 37 illustrated as mounted upon a shaft 38. This driving pulley carries upon it a double crank comprising a crank pin 39 and an arm 40 which extends diametrically across the face of the pulley 37, this arm at its end carrying a wrist pin 41. The link 34 is formed to provide a head 42 formed with a longitudinally extending slot 43, and the link 35 is formed with a like head 42 having a longitudinally extending slot 43. The pin 39 passes through the slot in the head 42 and the pin 41 passes through the slot in the head 42. The pulley or disk 37 is rotated in the direction of the arrow by means of a band 44 or by any other suitable mechanism and as it rotates it will be obvious from Figures 5 and 6 that one link will be drawn downward while the other link will be raised by means of a spring 45.

When the pulley or disk 37 is in the position shown in Figure 6, the pins 39 and 41 are horizontally disposed and both of the moistening members are raised and held raised under the action of the springs 45, these springs being shown as being connected to the depending arm of the respective bell crank levers. As the pin 39 moves downward it pulls down on link 42, thus lowering the corresponding moistening member, but pin 41 rides through the slot of the link 42 without effecting the moistener connected thereto, which is thus kept in its raised position. On the next quarter turn the link 42 will simply swing laterally without any effect upon the moistener, but the link 42 will rise as the pin 41 rises, thus lowering the other moistening member. Thus it will be seen that during one portion of the travel of the disk 37 both the moistening members will be raised. This is the position shown in Figure 6. Upon the further

movement of the pulley disk 37, one of the moistening members will be lowered, the other remaining raised, then the lowered moistening member will be raised, and then the first named moistening member again lowered. Thus there is always a raised moistening member with which the yarn comes in contact.

While I have illustrated the springs 45 as being applied to the depending arms 29 of the bell crank levers 30, I do not wish to be limited to this, as they might be applied to any other part of the mechanism and act to urge the moistening members in one direction or the other.

The general operation of this mechanism will be understood from what has gone before. The moistening members will be alternately raised from the water and immersed in the water. When raised they will apply moisture to the yarn to a slight amount. The yarn traveling over the moistening members receives water therefrom and is uniformly and adequately moistened. I have illustrated the pulley 37 as being driven by a belt 44 extending over idle pulleys 46 (see Figure 1) and then extending around a horizontal pulley 47 mounted upon a shaft 48, which in turn carries a worm gear 49 driven by a worm shaft 50, this worm shaft 50 constituting an extension of the shaft 51 ordinarily found in machines of this character which carries the main pulley 52 from which the cone driving means is operated by a belt 53. The shaft 51, the cone pulleys 52, the belt 53 and the allied parts are common in all winding machines and form no part of my invention and, therefore, need no particular description.

It will be understood that I do not wish to be limited to the details of construction illustrated, my invention consisting not so much in the mechanism employed for securing the raising and lowering of the moistening members as in the use of moistening members which are alternately immersed in the tank and raised therefrom into contact with the yarn. Moistening members of this character do not collect lint as rollers do, and furthermore they may be readily cleaned by the operator wiping them longitudinally with a rag when the machine is being doffed. Furthermore, there is obviously no danger of the yarn wrapping around the moistening members in case the yarn should break, which the yarn would be liable to do if rollers were used as moistening members. I have not attempted to illustrate all of the detailed construction of a winding machine, the traverse mechanism, and yarn guiding mechanism, but it will be understood that any of the ordinary means is used for this purpose.

It will be noted that the moistening members are formed on their side walls with

outwardly projecting ribs 20^a which engage with the lateral walls of the trough so as to space the moistening members from the walls of the trough, and that the moistening members are provided upon their confronting faces with the spacing ribs so that the moistening members are spaced from each other, thus permitting the ready movement of the moistening members into and out of the water and permitting the water to have free access to the tops of said moistening members.

While I have especially designed this moistening means for use in the conditioning or treating of yarn as it is being wound in a winding machine, I do not wish to be limited to the use of this device with a winding machine as it might be used with any machine through which yarn is passing and during any period in the treatment of the yarn. Thus the yarn may be moistened as it is being wound in hanks or it might be moistened by this means as it is passing to a drum or after it has passed over the drum of a slasher or while it is being twisted. Obviously the device might be used for dyeing yarn while the yarn is passing over the trough, the trough containing dyestuff, this dyestuff being applied to the yarn by means of the moistening members.

Preferably a splash pan or drip pan is used with the trough 16 and, as illustrated in Figure 3, this drip pan, which is designated 54, may be made in one piece with the trough. It will be understood that there is a drip pan or splash pan between each spindle and corresponding cone. There might, however, be a drip pan extending entirely along beneath all of the ends or yarn threads on the winding machines. This drip pan 54 extends to a point just beneath the small rod on the winder and designated 13 and over which the yarn passes. The yarn passing over the moistening members first comes in contact with this small rod 13 before passing onto the cones. The vibration of the wet yarn throws off some little water just before reaching this rod and this water would ordinarily fall upon the winder mechanism just below. Furthermore, as the yarn comes from the trough and the yarn comes in contact with the rod 13, water is deposited on this rod and drops from this rod onto the winder. It is to avoid this that I provide the splash pan 54 which catches the water dripping from the rod and also the water dripping from the yarn and carries it back to the trough.

I do not wish to be limited to this, as the splash plate illustrated in Figure 3 and designated 54 might be a separate piece from the trough. In this case, the splash plate is shown as formed with two flanges or jaws 55 which grip the wall of the trough so as to support the splash plate. This per-

mits the splash plate to be readily removed when the machine is to be cleaned. I do not wish to be limited to any particular design for this splash plate or pan nor to the material of which it is formed, nor to the manner in which it is mounted, and it is to be understood that the splash plate might be attached to any suitable portion of the winder instead of to the trough and yet be within the purview of this invention.

In Figure 12, I have illustrated a moistening member designated 20^b, the equivalent of the members 20 or 21, which is U-shaped in cross section, as are the members 20 and 21, but which has certain portions, designated 55 in Figure 12, over which the yarn or thread traverses, which portions are rounded at their ends by downwardly and laterally extending beveled faces 56. The yarn is caused to traverse these faces 55 by the transverse motion of the winder and the length of this portion 55 is such that the yarn in its traverse will move down onto the beveled face 56 alternately at one end or the other so that any lint which may have collected upon the face 55 over which the yarn moves will be swept off this face 55 at each traverse of the yarn in one direction or the other and will be carried down upon the inclined face 56. Then as the moistening member is lowered into the water the inrush of water past or across this beveled face 56 and the notches which form them will wash away this lint.

It will be understood that the angle between the face 55 and the face 56 is not sharp and cutting but that the two faces 55 and 56 merge into each other and the junction is rounded and smooth so that the yarn as it travels from right to left or left to right will pass downward and over these rounded edges and onto the beveled face 56, thus discharging lint from the face 55 over which the yarn traverses. It will be understood that there are as many faces 55 upon the moistening member 20 or 21 as there are spindles. Openings 57 corresponding to the openings 24 will be made in the reversely beveled faces 58 of the notch or groove or at any other point to permit the easy depression of the members into the liquid in the trough. In Figures 13 and 14, I show a modified form of the moistening member designated 20^c which is substantially like the construction illustrated in Figure 12, but in which these beveled faces 56 are not only beveled downward but the corners or edges are rounded, as at 56^a, so as to permit the traverse of the yarn with the least possible obstruction. It will be noted also that while the upper face of the moistener conforms, generally speaking, to the plane of travel of the yarn, yet the upper face is also slightly rounded, as shown most clearly in the relatively large views, Figures 11 to 13, so that

there shall be no obstruction to the travel of the yarn and no tendency to cut the yarn.

It is reiterated that I do not wish to be limited to any particular material for these members 20 and 21, whether constructed as illustrated in Figures 9 and 10 or as these moistening members 20^b and 20^c are illustrated in Figures 12 and 13, nor do I wish to be limited to any specific manner of raising or lowering these members except as defined in the appended claims.

I claim:—

1. Yarn moistening means including a trough adapted to contain liquid and disposed beneath the traveling yarn, a moistening member disposed in the trough, and power operated means for vertically reciprocating the moistening member to cause it to be alternately raised into contact with the 20 yarn and lowered bodily downward into the liquid in the trough.

2. Yarn moistening means including a trough adapted to contain liquid and be disposed beneath the travelling yarn, a plurality of moistening members disposed in the trough and mounted for movement in a plane approximately at right angles to the yarn, and means for bodily reciprocating each moistening member toward and from 30 the yarn to cause the moistening member to be alternately immersed in the liquid and raised into contact with the yarn, said means including means for holding each moistening member stationary in contact with the 35 yarn until the other moistening member has been brought into contact therewith.

3. Yarn moistening means including a trough adapted to contain liquid and to be disposed beneath the traveling yarn, a plurality of moistening members disposed in the trough, means for operating each moistening member to cause it to be alternately immersed in the liquid and raised into contact with the yarn, said means including 40 means for holding a moistening member in contact with the yarn during the time that the other moistening member is traveling downward into the liquid and raising therefrom into contact with the yarn.

50 4. Yarn moistening means including a trough adapted to contain liquid and to be disposed beneath the traveling yarn, a plurality of longitudinally extending moistening members mounted in the trough, and means for intermittently bodily raising and lowering said moistening members to alternately bring them into contact with the yarn and immerse the moistening members and including means for holding one of said 55 moistening members in contact with the yarn until the other moistening member after its immersion has been brought into contact with the yarn.

55 5. Yarn moistening means including a trough adapted to contain liquid and to be

disposed beneath the traveling yarn, a longitudinally extending moistening member disposed in the trough and having an upper surface adapted to hold water and at all times disposed in a horizontal plane, and 70 means for alternately raising the moistening member into contact with the yarn and lowering the moistening member to immerse it in the liquid in the trough.

6. Yarn moistening means including a 75 trough adapted to contain liquid and to be disposed beneath a traveling yarn, a plurality of moistening members disposed in the trough, each of said members consisting of a plurality of longitudinally aligned sections 80 operatively connected to each other for coincident longitudinal movement, cams formed upon the lower edges of said sections, and means for reciprocating the sections, and ribs on the bottom of the trough with which 85 the cam faces of the sections are adapted to engage whereby the moistening members may be raised or lowered.

7. Yarn moistening means including a trough adapted to contain liquid and to be 90 disposed beneath a plurality of traveling yarns, a plurality of moistening members disposed in the trough and extending beneath all of said yarns, each moistening member being formed upon its upper face to 95 retain a small amount of liquid, and means for reciprocating each moistening member, the moistening members being formed upon their under edges with inclined cam faces and the trough being formed with ribs upon 100 which said cam faces ride whereby to cause the upward vertical movement of each of said moistening members as it is reciprocated in one direction and the downward movement of each moistening member as it 105 is reciprocated in the other direction.

8. Yarn moistening means including a trough adapted to contain liquid and to be disposed beneath a plurality of traveling yarns, a plurality of moistening members 110 disposed in the trough and extending beneath all of said yarns, each moistening member being formed upon its upper face to retain a small amount of liquid, and means for reciprocating each moistening member being formed upon their under edges with inclined cam faces and the trough being formed with ribs upon which 115 said cam faces ride whereby to cause the upward vertical movement of each of said moistening members as it is reciprocated in one direction and the downward movement of each moistening member as it is reciprocated in the other direction, the operating 120 means for the moistening members including means for holding one of said members raised into contact with the yarn until the other member has been raised into contact with the yarn and then lowering the first 125 named member.

9. Yarn moistening means including a trough adapted to contain liquid and to be disposed beneath a plurality of traveling yarns, a pair of moistening members disposed in the trough, each moistening member having an upper corrugated face adapted to retain a small amount of liquid, and constantly operated means for bodily alternately raising and lowering each moistening member into contact with the yarn and including means for holding each one of said members in contact with the yarn until the other moistening member has been raised into contact with the yarn. 65
10. Yarn moistening means including a trough adapted to contain liquid and to extend longitudinally beneath a series of traveling yarns, a pair of moistening members disposed in the trough and held spaced from the sides thereof and from each other, each of said moistening members having the form in cross section of an inverted **U** to provide depending side walls, each of said side walls having a series of cam faces formed thereon, 70
20. a series of ribs carried by the trough with which said cam faces are adapted to engage, and power operated means for reciprocating said moistening members to cause them to rise from the liquid in the trough into contact with the yarn or to move away from the yarn and be immersed in liquid in the trough, said means including means for holding each one of said moistening members in contact with the yarn until the other moistening member has risen into contact 75
30. with the yarn. 80
35. 11. Yarn moistening means including a trough adapted to contain liquid and to be disposed beneath the traveling yarn, a longitudinally extending moistening member disposed in the trough, and means for alternately raising the moistening member into contact with the yarn and lowering the moistening member to immerse it in the liquid in the trough, the moistening member being formed with a portion over which the yarn passes, this portion having a face equal in length to the traverse of the yarn, the ends of this portion being downwardly and laterally beveled. 85
40. 12. The combination with a yarn winding machine, a member on which the yarn is wound and a traveler reciprocating in front of said member and acting as a guide for the yarn, of a trough extending longitudinally beneath the yarn, a moistening member mounted in the trough and adapted to be alternately raised into contact with the yarn and lowered out of contact therewith and immersed in the liquid in the trough, and means for alternately raising and lowering the moistening member, the moistening member being formed with a face over which the 90
45. 13. The combination with a yarn winding machine, a member on which the yarn is wound and a traveler reciprocating in front of said member and acting as a guide for the yarn, of a trough extending longitudinally beneath the yarn, a moistening member mounted in the trough and adapted to be alternately raised into contact with the yarn and lowered out of contact therewith and immersed in the liquid in the trough, and means for alternately raising and lowering the moistening member, the moistening member being formed with a face over which the 95
50. 14. The combination in a winding machine, of a member upon which the yarn is to be wound, means disposed immediately beneath said member for giving a traverse to the yarn, of a trough disposed immediately beneath the traveling yarn, a plurality of independently movable moistening members disposed in the trough, means for operating each moistening member to cause it to be alternately immersed into the liquid and raised into contact with the yarn, and a splash pan extending from one wall of the trough to a point beneath the means upon which the yarn is wound to receive the drippings therefrom. 100
55. 15. The combination in a winding machine, of a member upon which the yarn is to be wound, means disposed immediately beneath said member for giving a traverse to the yarn, of a trough disposed immediately beneath the traveling yarn, a plurality of independently movable moistening members disposed in the trough, means for operating each moistening member to cause it to be alternately immersed into the liquid and raised into contact with the yarn, and a splash pan extending from one wall of the trough to a point beneath the means upon which the yarn is wound to receive the drippings therefrom, said splash pan being carried by the trough. 105
